(57) **CLAIM**

The ornamental design for a video camera, as shown and described.

DESCRIPTION

FIG. 1 is a front perspective view of a video camera showing the new design.

FIG. 2 is a rear perspective view of the video camera shown in FIG. 1.

FIG. 3 is a front elevation view of the video camera shown in FIG. 1.

FIG. 4 is a rear elevation view of the video camera shown in FIG. 1.

FIG. 5 is a left side elevation view of the video camera shown in FIG. 1.

FIG. 6 is a front perspective view of a video camera, shown with a base and an arm disclosed in broken lines to illustrate an environment.

FIG. 7 is a front perspective view of a video camera, shown with an AC power plug disclosed in broken lines to illustrate an environment; and,

FIG. 8 is a front perspective view of a video camera, shown with side grippers disclosed in broken lines to illustrate an environment.

The broken lines depict portions of a video camera in which the design is embodied that form no part of the claimed design. The broken lines showing a base, arm, AC power plug and side grippers in FIGS. 6–8 represent environmental structure that form no part of the claimed design. The dash-dotted lines define the boundary of the claimed design in FIGS. 1, 3 and 7, and does not form part of the claimed design.
